UNITED STATES PATENT OFFICE.

DANIEL A. WIGHTMAN, OF PITTSBURG, PENNSYLVANIA.

LOCOMOTIVE-FRAME.

SPECIFICATION forming part of Letters Patent No. 657,230, dated September 4, 1900.

Application filed June 28, 1900. Serial No. 21,884. (No model.)

To all whom it may concern:

Be it known that I, DANIEL A. WIGHTMAN, of Pittsburgh, in the county of Allegheny and State of Pennsylvania, have invented a certain 5 new and useful Improvement in Locomotive-Frames, of which improvement the following is a specification.

The object of my invention is to provide simple, strong, and inexpensive means for 10 connecting together and bracing the forward portions of the side members of a locomotive-frame and for securing the cylinder-saddles more firmly thereto than heretofore and transferring to the frame a portion of the strain 15 which has ordinarily been sustained by the cylinders and their saddles.

The improvement claimed is hereinafter fully set forth.

In the accompanying drawings, Figure 1 is 20 a plan or top view of the forward portion of a locomotive-frame and the connected left-hand cylinder and saddle, illustrating an application of my invention, the lower half of the figure being in horizontal section on the line *a a* of Fig. 2 and the right-hand cylinder and saddle being omitted to promote clearness of illustration; Fig. 2, a vertical longitudinal central section; Fig. 3, a transverse section, the left-hand half being taken on the 25 line *b b* of Fig. 2 and the right-hand half on the line *c c* of Fig. 1; Fig. 4, a transverse section at the line *d d* of Fig. 2; Fig. 5, a plan or top view of the cylinder brace-plate detached, and Fig. 6 a vertical longitudinal section at the line *e e* of Fig. 1.

The main portion of each of the side members of the frame—that is to say, that portion which extends from the front pedestal to the rear end of the frame—is herein shown as of 40 the construction ordinarily heretofore employed, consisting of a rectangular main-frame bar or rail 1, having downwardly-depending pairs of jaws or pedestals 2, the pedestals of each axle being connected by intermediate pedestal-braces 3 to those of the next axle and being provided with removable shoes 4. Downwardly-projecting members 5, which serve as saddle-bearings, against which the cylinder-saddles abut on their rear sides, are 45 formed upon the forward ends of the main-frame bars 1 and are connected at their lower

ends to the forward pedestals by horizontal lower bars 6, continuous rigid vertical bearings or abutments for the saddles being thus provided and the portions of the main frame 55 in advance of the forward pedestals being made integral rectangular structures. The forward portion of each of the side frame members, to which the adjacent cylinder-saddle 7 is connected and which may be termed 60 the "cylinder-section" of the frame, is composed of an upper frame bar or rail 8, secured to the main-frame bar 1 by bolts 9 and keys 10, and a lower frame bar or rail 11, secured to the lower bar 6 of the main frame by bolts 65 12 and keys 13. The frame-bars 8 and 11 extend forward horizontally for a sufficient distance to admit the cylinder-saddles, at the front of which they are extended downwardly and upwardly, respectively, for sufficient distances either to abut on their adjoining faces or, preferably, as shown, to fit truly against the upper and lower sides of an interposed transverse front brace-plate 14. The frame-bars 8 and 11 and front brace-plate 14 extend 70 longitudinally in front of the saddles to a suitable bumper-beam, to which they are secured at their front ends.

A transverse cylinder brace-plate 15 extends across the frame below the cylinder- 80 saddles 7, its front end being in or about in line with the front thereof and its rear end being located as close to the inside of the forward jaws of the front pair of pedestals 2 as will properly clear the inner flanges of the 85 driving-axle boxes. The upper and lower faces of the brace-plate 15 are finished truly at and near its sides preferably with shoulders at the inner sides of the finished portions, and said brace-plate is fitted and secured 90 between flanges or brackets 16, formed on the inner sides of the lower bars 11 of the cylinder-section of the frame, and corresponding flanges or brackets 17 on the inner sides of the lower bars 6 of the main frame. The 95 brace-plate 15 is rigidly connected to the frame-bars 6 and 11 by the keys 13, by the bolts 12, by bolts 18, passing through it and through the flanges 16 and 17, and by bolts 19, passing through it and through the flanges 100 16. The cylinder-saddles 7 may be secured to the bars 8 and 11 of the cylinder-section

of the frame in the usual or any approved manner and are independently secured to the cylinder brace-plate 15 by bolts 20.

5 A rectangular slot 21 may be formed centrally in the plate 15 near its rear end for the purpose of allowing the back end of the equalizer in locomotives having two-wheeled trucks to project through sufficiently far for the attachment of the equalizer-hanger.

10 The cylinder brace-plate 15 is, it will be observed, located nearly in the horizontal plane of the axes of the cylinders 22, thus relieving the upper frame-bars of a substantial portion of the strain which they ordinarily sustain. The plate 15 forms an additional tie leading directly to the cylinder-saddles, which are connected to it both independently of the frame-bars and intermediately through said bars, and a portion of the strains ordinarily sustained by the splice-bolts is thereby transferred to the main frame, thus materially strengthening the frame and cylinder connections, which is a matter of substantial importance in large engines hauling extremely heavy trains, as in present approved practice. The plate 15 also constitutes a rigid longitudinal and transverse brace extending back from the front of the saddles as nearly to the first driving-axle as practicable.

15 30 In the instance exemplified my improvement is described and shown as applied in connection with cylinders of the type which is now practically standard--that is to say, in which each cylinder is cast integral with a saddle, the two saddles abutting and being secured together in the vertical longitudinal central plane of the locomotive and having their upper faces curved in conformity with the smoke-box, which is supported upon and bolted thereto. It will, however, be apparent that my invention is equally applicable in locomotives having a central bed-plate or saddle and separate cylinders secured to each side thereof, a construction which is in use

20 45 to a comparatively-slight extent. I therefore use the term "saddles" herein as referring to the member which is intermediate of the cylinders, whether the same is composed of two parts each integral with one of the cylinders or is a single casting having a separate cylinder secured to each of its sides, said two constructions being so far as my invention relates thereto mechanical equivalents.

50 55 The front brace-plate 14 is fitted between lateral flanges 23, formed on the lower portion of the upper bar 8 of the cylinder-section of the frame, and similar flanges 24 on the upper portion of the lower bar 11 thereof and is rigidly secured thereto by bolts 25. The flanges 23 and 24 are turned upwardly and downwardly, respectively, at their front ends, so as to afford a wide bearing for the entire depth of the frame-bars 8 and 11 against the rear side of the bumper-beam, against which the front brace-plate 14 also abuts throughout its entire width, so as to

constitute a strong brace for the bumper-beam substantially from one end thereof to the other. A suitable center casting 25^a for 70 the reception of the center pin of the truck may be secured to the plate 14.

75 While it will be obvious that an ordinary wooden bumper-beam may, if desired, be employed, the bumper-beam is, in order to insure greater strength and rigidity in the front portion of the frame, preferably a composite metal structure formed of two transverse channels 26, having their flanges turned outwardly and separated by interposed distance-blocks 27 and connected to the front frame-bars 8 and 11 and brace-plate 14 by angle-bars 28 and bolts or rivets 29. The bumper-beam is further stiffened by upper and lower plates 30 31.

80 85 The construction above described imparts great strength and stiffness to the forward portion of the frame and the connections of the cylinder-saddles thereto. The attachment of the cylinder-saddles to the frame intermediately through the cylinder brace-plate additionally to the ordinary direct connections and the bracing of the cylinders by said plate close to the line of strains in service materially lessens the liability to breakage of cylinders or looseness of connecting-bolts, which has heretofore obtained to such an extent as to result in frequent and considerable damage and expense.

90 95 I claim as my invention and desire to secure 100 by Letters Patent—

1. In a locomotive-frame, the combination of two main-frame side members, a pair of cylinders having interposed saddles, a transverse cylinder-frame brace extending below 105 the saddles, from the front thereof to or near the forward pedestals of the frame, connections securing the cylinder-frame brace to the side frame members, and connections independently securing the cylinder-frame 110 brace to the saddles.

115 2. In a locomotive-frame, the combination of two main-frame side members, a pair of cylinders having interposed saddles, a transverse cylinder-frame brace located adjacent 120 to the horizontal plane of the axes of the cylinders and extending from the front of the saddles to or near the forward pedestals of the frame, connections securing the cylinder-frame brace to the side frame members, and connections independently securing the cylinder-frame brace to the saddles.

125 3. In a locomotive-frame, the combination of two main-frame side members, two forward frame bars or rails, and a transverse cylinder-frame brace, interposed at its sides between, and connected to, the main-frame side members and the forward frame-bars, and extending from the plane of the front of the saddles to or near the forward pedestals of the frame.

130 4. In a locomotive-frame, the combination of two main-frame side members, each having a lower horizontal flange on its inner side, two forward frame bars or rails, each having

an upper horizontal flange on its inner side, and a transverse cylinder-frame brace interposed at its sides between, and connected to, the flanges of the main-frame side members 5 and of the forward frame-bars.

5. In a locomotive-frame, the combination of two main-frame side members, upper and lower forward frame bars or rails, secured to the side frame members and having horizontal flanges on their adjacent faces, and a transverse front brace-plate, interposed at its sides between, and secured to, the flanges of the forward frame-bars, and extending from the front ends thereof to or near the 15 plane of the front of the saddles.

6. In a locomotive-frame, the combination of two main-frame side members, upper and lower forward frame bars or rails secured to the side frame members, a transverse front brace-plate interposed at its sides between, and secured to, the forward frame-bars, and extending from the front end thereof to or near the plane of the front of the saddle, a 20 bumper-beam composed of two channel members and interposed distance-blocks, and an- 25

gle-bars secured to the front brace-plate and to the adjacent channel member of the bumper-beam.

7. In a locomotive-frame, the combination of an upper main-frame bar or rail, downwardly-depending jaws or pedestals, a vertical saddle-bearing projecting downwardly from the upper main-frame bar, at the forward end thereof, and a lower frame bar or rail connecting the lower end of the saddle- 30 35 bearing with the adjacent jaw.

8. In a locomotive-frame, the combination of an upper main-frame bar or rail, downwardly-projecting-jaws or pedestals, a lower main-frame bar or rail projecting in advance 40 of the forward jaw, and a vertical member interposed between and connecting the forward ends of the upper and lower main-frame bars, and forming therewith and with the forward jaw, an integral rectangular structure. 45
